H. T. BUSSMANN

ELECTRIC FUSE

Filed May 7, 1919

INVENTOR

HENRY T. BUSSMANN

by *T. G. McRae* ATTORNEY.

UNITED STATES PATENT OFFICE.

HENRY T. BUSSMANN, OF ST. LOUIS, MISSOURI.

ELECTRIC FUSE.

Application filed May 7, 1919. Serial No. 295,369.

To all whom it may concern:

Be it known that I, HENRY T. BUSSMANN, a citizen of the United States, residing at St. Louis, Missouri, have invented a certain new and useful Electric Fuse, of which the following is a full, clear, and exact description, such as will enable others skilled in the art to make and use the same.

My invention relates to electric fuses and refers particularly to that type of fuse known as the refillable cartridge knife blade type; yet I do not limit my invention to this type as certain of my improvements are likewise desirable in other types of fuses.

It is well known that fiber, which is principally used as a casing, will shrink and swell, making it difficult to provide removable closures for the casing, that are satisfactory. For this reason, I provide a member attached to each end of the casing, preferably of metal or other material of unchanging dimensions, for the holding of the closures.

This member also serves to eliminate the difficulties experienced by the edgewise movement of the terminals caused by inserting the fuse into the jaws of a fuse block. This edgewise movement results in injury to the fuse link or loosening of its fastenings, resulting in poor contact, and consequent premature burn-out of the fuse-link.

Another object of my invention is to provide a means for assuring the assemblage of the terminals and fuse link in a straight line. The difficulty has been that when the bolt intended for this purpose is pulled up tight, it invariably pulls the terminals out of line with the link, making it impossible to assemble the fuse.

These and other advantages of my invention will be more readily understood by reference to the accompanying drawings, which show a preferred form of my invention.

In describing the device shown in the drawings hereto attached and described in the specifications, I do not limit my invention to the precise form, shape or construction of the fuse shown, or to the several parts thereof, as various alterations can be made without changing the scope of my invention.

Fig. 1 is a view of my fuse having a section broken out to show the interior arrangement thereof. Fig. 2 is a like view showing the interior of the fuse ninety degrees removed from that shown in Fig. 1. Fig. 3 is an end view of the fuse. Fig. 4

shows a terminal and part of a fuse strip with means for securing and aligning the terminal and strip. Fig. 5 shows a modified form of my improved fuse.

In the drawings, 5 is a casing, 6 is a member extending partially within the casing. As shown in the drawings, this member is in the shape of a ring having a shoulder thereon. It is obvious that various changes may, however, be made in the shape of this member, and while I prefer to use a member fitted inside the casing, yet, I may use one fitted outside, although the latter is unsatisfactory because the fiber shrinks away from it. 7 is a portion of the outer periphery, which is threaded to engage and hold the casing. 8 is a closure. 9 are screws which attach the closure 8 to the member 6. This closure may be in the form of a cap having side walls.

Through the slot 10 of the closure 8 there extends the terminal 11. On the interior of the member 6, I provide bearing points having a spaced relation to each other, between which points the terminal is positioned with only a limited clearance. When the terminal is subjected to edgewise movement, as, for instance, when a fuse is inserted in a fuse block, the terminal will bear on the points 16, 16', or 17, 17', and by reason of the separation of these points and the small clearance allowed the terminal, only a very limited movement of the terminal is permitted. The member must be made of a material of practically unchanging dimensions as to maintain these dimensions constant. Fiber, as now made, cannot be used for this purpose as the shrinking or swelling of the fiber would not maintain this constant clearance and would cause the terminals to bind. Obviously, instead of a member in the form of a ring, I may use a broken ring. It is only necessary that the bearing points shall be separated by spaces practically constant.

The terminal 11 and fuse strip 12 are connected by means of a bolt 13, which passes through the holes in the terminal and fuse strip. 14 is a projection preferably stamped out of the terminal, as shown in Fig. 2, and 15 is a recess in the fuse strip to engage with the projection 14. When so positioned the terminal and fuse strip are rigidly held in predetermined alignment and cannot be pulled out of such alignment when fastening the bolts.

To hold the terminal against longitudinal

movement, I provide a terminal holding device, preferably a bar, as shown at 18, which is located on the outside of the closure, although I may place this bar under the closure, in which case I would prefer to recess the member to position the bar. This bar is held by the closure holding screws 9 and fits into slot 19 in the terminal. I prefer to make this slot of a length greater than the thickness of the bar. By this means I am able to adjust any variation in the length of the fusible element comprising terminal and fuse link, or variations in length of the casing, occasioned by the shrinkage of the fiber. It is obvious that I may make this slot of only such a length as to just fit the bar, if other means are provided to prevent or adjust the variations mentioned.

Any suitable form of fuse link may be used in my fuse.

I claim as my invention:

1. In an enclosed fuse, a casing, a member permanently attached to the casing, a flat-blade terminal adapted to be passed through said casing, a closure and means extending through the end face of the member for detachably securing the closure.
2. In a refillable fuse, a tubular casing, a member having a threaded portion for securing to the casing, a terminal adapted to be removably positioned within the casing, a closure fitted about the terminal, and means on the end face of the member for detachably securing the closure to the end of said member.
3. In a refillable fuse, a casing, a ring-shaped member having its inner periphery of constant dimension, a flat-blade terminal adapted to be passed through the member and removably fitted, with a certain limited clearance within the member and held

against edgewise movement relative to the member.

4. In a refillable fuse, a casing, a ring-shaped member, a flat-blade terminal adapted to pass therethrough, said member having oppositely disposed means in constant spaced relation to each other between which the terminal at its edges is removably positioned with a certain limited clearance, whereby edgewise movement of the terminal is substantially prevented.

5. In an enclosed fuse, a casing, a member attached to the casing permanently, a terminal extending within said member, said terminal having an aperture outside of said member, a terminal holding device secured to said member and engaging said aperture to limit the longitudinal movement of said member.

6. In a fuse, a casing, a closure, a terminal and a device outside the closure adapted to hold the terminal against inward and outward movement.

7. In a fuse, a casing, a terminal having an aperture therein, a terminal holding device engaging said aperture, said engaging portion of the device having such a lesser width than the length of the aperture as to permit a certain limited longitudinal movement of the terminal relative to the terminal holding device.

8. In a refillable fuse, a structure comprising a casing and closures therefor, a pair of terminals and a fuse link connected to form a fusible element, there being an aperture in the terminal and terminal holding device engaging said aperture and permitting a certain limited longitudinal movement of the terminal relative to the terminal-holding device.

HENRY T. BUSSMANN.
